UNITED STATES PATENT OFFICE.

ARCH A. SHINGLETON, OF CINCINNATI, OHIO.

AUTOMATIC TIME-VALVE.

No. 883,121.

Specification of Letters Patent. Patented March 24, 1908.

Application filed May 27, 1907. Serial No. 375,797.

To all whom it may concern:

Be it known that I, ARCH A. SHINGLETON, a citizen of the United States, residing at Cincinnati, in the county of Hamilton and State of Ohio, have invented certain new and useful Improvements in Automatic Time-Valves, of which the following is a specification.

My invention relates to clock controlled mechanisms, the object being to alternately open and close a valve automatically at predetermined times.

My invention consists in a crank in operative connection with a valve to be opened and closed, a valve operating motor, operative connection between said crank and said valve operating motor, a clock mechanism, cams adapted to be rotated uniformly by said clock mechanism, stops for said valve operating motor, and cam levers in engagement with and controlled by said cams, adapted to engage and control said stops, and in the combination and arrangement of parts as will hereinafter be more fully described and claimed.

In the drawings: Figure 1 is a front elevation of the interior mechanism of my invention. Fig. 2 is a bottom plan view of my invention, the front part of the case being represented in section. Fig. 3 is a cross section on the line $x-x$ of Fig. 1, showing how the stops are mounted. Figs. 4 and 5 are front views of my invention with the dials in place to illustrate the positions of the various parts at different stages of its operation, certain parts not important to this illustration being omitted. Fig. 6 is a vertical section on the line $y-y$ of Fig. 2, the valve and its operative connections with the valve operating motor being shown in elevation, as is also the setting arm of the cam lever setting mechanism. Fig. 7 is a detail perspective view of the setting arm of the cam lever setting mechanism. Fig. 8 is a rear elevation of my invention, part of the case being represented as broken away but having its outlines represented by dotted lines. Fig. 9 is a detail perspective view of the valve arm and its adjustable connection. Fig. 10 is a detail perspective view of the valve and its stock adapted to receive the adjustable connection of the valve arm. Fig. 11 is a perspective view of part of the front plate with the hour hand gears mounted thereon and showing one of the cam gears about to be slipped onto its spindle. Fig. 12 is a detail perspective view of the crank shaft

with the crank shaft gear and crank disk mounted thereon. Fig. 13 is a sectional view illustrating the method of adjustably pivoting the connecting rod to the valve arm. Fig. 14 is a detail perspective view of the apron. Fig. 15 is a sectional view showing how the cam gears are mounted.

Preferably my invention is constructed as follows:

A frame 1 comprising a rear plate 2, front plate 3, and posts 4, forms a support and bearings for an ordinary clock mechanism 5 preferably having the main spring 6 with its winding mechanism 7 and primary gear 8. 70 The primary gear 8 meshes with the pinion 9 rigid on the shaft 10 with the intermediate gear 11, which meshes with the pinion 12 rigidly mounted upon the shaft 13, which carries the minute hand 14. The third wheel 75 15 is rigidly attached to the pinion 12, and likewise a fourth wheel 16 is attached to a pinion 16^a, in mesh with the third wheel 15, and revolves the escapement 17 by means of the fifth wheel 18, the pinion 18^a and the 80 pinion 17^a on the escapement wheel shaft. The escapement wheel is controlled by the usual hair spring 19 and balance wheel 20, by means of the escapement lever 21, and a regulator 22 is provided upon the front 85 plate 3. Also the usual train of gears 23 is provided for revolving the hour hand 24, this train of gears consisting of the pinion 25 rigidly mounted upon the shaft 13, the wheel 26 pivotally mounted on the stud 27 90 in the front plate 3, the pinion 26^a rigidly and concentrically attached to the wheel 26 and the wheel 28 in mesh with the pinion 26^a pivotally mounted on the shaft 13 and having the hub 28^a which carries the hour hand 24. 95

The above description of the clock mechanism is given only for the purpose of facilitating the succeeding references to the parts thereof and I do not wish to be understood as claiming said clock in itself, as my invention, 100 any of the usual clock mechanisms being adapted for use in combination with my invention. This use is accomplished by providing the right and left cam gears 29 and 30 which mesh with the pinion 26^a, and, being 105 provided with twice as many teeth as has the wheel 28 which revolves the hour hand 24, these cam gears 29 and 30 will be revolved only once in twenty four hours instead of twice in that time as is the hour hand 24. 110 The cam gears 29 and 30 are rotatably mounted on the hollow cam shafts 31 and 32,

which are provided with flat springs 33 and 34 rigidly mounted thereon and held against the faces of the cam gears 29 and 30 between the inner collars 35 and 36, which are preferably integral with the cam shafts 31 and 32, and the cams 37 and 38 which are rigidly secured on the cam shafts 31 and 32 by means of the set screws 39 and 40. It will thus be seen that while the cam gears 29 and 30 are revolved by the clock mechanism through the pinion 26^a, the cams 37 and 38 are revolved by the cam gears 29 and 30 through the frictional contact of the springs 33 and 34 with the faces of the cam gears 29 and 30. This frictional contact allows the cams to be rotated manually, independently of the clock mechanism. The hollow cam shafts 31 and 32 are journaled on the cam studs 41, which are supported by the front plate 3.

For opening and closing the valve which is represented at 42, and which has the stock 43, I prefer to use as a motor, the spring 44 mounted on the shaft 45 with the primary gear 46, having a winding mechanism 47. The shaft 45 has its forward ends squared, as at 48, and preferably of the same size and shape as the forward end 49 of the shaft 50 of the clock main spring 6, so that the same key may be used for winding either the clock main spring 6 or the valve operating main spring 44. The dial plate 51 is mounted on posts 51^a. The shafts 45 and 50 extend through the dial plate, as do also the shaft 13, which carries the minute hand 14 and the hour hand 24 in front of the dial plate 51, and the cam shafts 31 and 32 which are provided with the thumb knobs 52 and 53 rigidly mounted thereon in front of the dial plate 51, for manually rotating the cams 29 and 30.

In mesh with the primary gear 46 is the crank shaft gear 54, rigidly mounted upon the crank shaft 55. The primary gear 46 is also in mesh with the pinion 56, which is rigidly attached to the first gear 57. The first gear 57 meshes with the pinion 58, which is rigidly attached to the second gear 59. The second gear meshes with the pinion 60, and the pinion 60 is rigidly attached to the third gear 61, which meshes with the pinion 62 on the controller shaft 63, which carries the controller 64, constituting a controlling device for the valve operating spring 44, this controlling device being similar to that used with the striking mechanism of the ordinary clock, and which I do not claim, in itself, as my invention.

The crank shaft 55 is journaled rearwardly in the strap 65, secured to the lower part of the rear plate 2, and forwardly in the upward extension 66 of the apron 67, which is secured to the lower part of the front plate 3, the crank shaft gear 54 being secured rigidly upon this crank shaft 55 between the front and rear plate by means of a set screw taking through the hub 68 of the crank shaft gear 54. To the rear of the strap 65 the ratchet wheel 69 is rigidly attached to the crank shaft 55, and the crank disk 70 is rotatably mounted on the crank shaft 55 to the rear of the ratchet wheel 69, with the pawl 71 in engagement with said ratchet wheel 69. The crank disk 70 has the radial slot 72 through which the wrist-pin 73 is adjustably secured to the crank disk 70. The valve crank 74 is secured to the stock 43 of the valve 42, and is also provided with a wrist-pin 75 similar to the wrist-pin 73, to both of which wrist pins 73 and 75 is pivotally attached the connecting rod 76. The crank 74 has the radial slot 77 through which the wrist-pin 75 is adjustably secured, these adjustments being provided to adapt the valve operating mechanism to valves requiring different degrees of turning of the valve stems in order to open or close them, this being necessary owing to the fact that the valve must always be opened or closed during one-half of a revolution of the crank shaft 55, which always revolves in the same direction, in this case from left to right. The ratchet 69 and pawl 71 are provided to allow the crank disk 70 to be adjusted to the proper position relative to the crank 74, independently of the crank shaft 55, the continuous revolution of the crank shaft 55 in one direction allowing such an adjustment to be used. The crank 74 is provided with the shank 78, which is journaled in a bushing 79 in the rear plate 80 of the case 81. To allow of the proper accuracy of adjustment between the shank 78 and the stock 43 of the valve 42, which is to be operated, I provide the sleeve 82 which is slipped onto the rearward part of the shank 78 and secured thereto by means of the set screw 83, thus permitting of adjustment longitudinally of the shank 78. To allow for slight variations of alignment between the valve 42 and the case 81, I pivot the yoke 84 to the sleeve 82, which is adjustably secured to the stock 43 of the valve 42 by means of the straps 85 and bolts 86, the stock 43 preferably having the recesses 87, which admit the bolts 86 and prevent total displacement of the parts while allowing of a slight slide adjustment depending upon the amount of clearance allowed.

The sheave 88 is rigidly mounted on the crank shaft 55 in front of the apron 67, and is provided with the radial lug 89 on its periphery. Adjacent the sheave 88 at either side are the stops 90 and 91. These stops are pivoted on bushings 92 on the apron 67, being held thereon by means of the washers 93 and tap screws 94. These tap screws also serve to hold the apron 67 in place upon the front plate 3 by taking through the bushings 92 and the apron 67, and through the front plate 3 into the posts 4, as is illustrated in Fig. 3 of the drawing. The stop 90, at the right of the sheave 88, is pivoted with its end

gaging face upward and substantially in horizontal line with the center of the sheave 88, while the stop 91, at the left of the sheave 88, is pivoted with its engaging face downward 5 and on the same horizontal line with the engaging face of the stop 90 at the right. The apron 67 is further secured to the front plate 3 by means of the screws 95 and 96, and the contractile spring 97 is also preferably secured to the screw 96 by one of its ends, and has its other end attached to the stop 91, near the outer end of said stop, through an opening 97^a therein. A fence 98 is provided for the stop 91 and is adjustably secured to 15 the front plate 3 by means of the screw 99. The stop 90 is also provided with a fence 100 adjustably secured to the front plate 3 by means of the screw 101, this screw 101 also preferably securing one end of the contractile 20 spring 102 which at its other end is secured to the stop 90, near its outer end, through the opening 103. The spiral springs attached to both of the stops 90 and 91 thus tend to draw the stops against the fences 100 25 and 98, respectively.

The apron 67 is provided on its upper part with the lateral extensions 104 and 105, upon which the cam levers 106 and 107 are pivoted by means of the screws 108 and 109, respectively. The cam lever 106 preferably has the end 110 inclined, which is adapted to come within the arc of rotation of the stop 90 and limit the movement of its outer end away from the fence 100. The cam lever 107 has at its lower end the inwardly extending guard 111 which preferably has an inclined upper surface 112 adapted to come under the outer end of the stop 91 and limit its rotation away from the fence 98. The movement of the stops 90 and 91 being limited by the lower parts of the cam levers 106 and 107, respectively, they are thus adapted to prevent the sheave 88 from turning when its radial lug 89 engages either of them. 40 When the radial lug 89 thus engages one of the stops, the outer end of the stop will tend to rotate away from its fence and if the lower end of the cam lever be moved outward, the force of the spring 44 exerted through the 45 intermediate parts upon the sheave 88 will cause the lug 89 by its engagement with the stop to rotate it against the tension of the contractile spring, allowing the lug 89 to pass.

The cam lever 106 has at its upward end 55 the inwardly and downwardly extending finger 113 while the cam lever 107 has the inwardly and upwardly extending finger 114. These fingers 113, and 114 are adapted to bear against the peripheries of the cams 37 60 and 38 respectively, and said cams 37 and 38 are provided with the recesses 115 and 116, respectively, the inwardly downwardly extending finger 113 and the inwardly upwardly extending finger 114 being so formed 65 that any will enter the recesses 115 and 116,

respectively, without interruption, when the cams 37 and 38, respectively, have rotated to the proper position. The cams 37 and 38 preferably rotate from left to right in the same direction as the hands of the clock, and the recesses are so disposed that the peripheries of the cams describe an acute turn at the sides of the recesses where the fingers are adapted to enter said recesses. This formation of the cams permits the fingers to enter 70 the recesses suddenly so that the lower ends of the cam levers will be thrown out to release the stops 90 or 91 quickly. 75

For holding the fingers in engagement with the periphery of the cams normally, the contractile springs 117 and 118 are secured to the cam levers 106 and 107, respectively, through openings 119 and 120, respectively, therein. The other ends of said contractile 80 springs 117 and 118 are secured to the setting arm 121 through the openings 122 and 123, respectively, therein near its upper end. This setting arm 121 is pivoted near its middle by means of the screw 124 on the bracket 125, said bracket being secured rigidly to the 85 front plate 3. The setting arm 121 has the slot 126 in its lower end over the hub 127 of the sheave 88, and an engaging pin 128 is placed eccentrically in said hub 127 and engaging within the slot 126 in the setting arm. 90 The setting bars 129 and 130 are pivoted to the setting arm 121 at its upper end and extend laterally to the cam levers 106 and 107 respectively, where they have slots 131 and 132, respectively, in which engage the pivotal 95 screws 133 and 134, respectively. The engaging pin 128, in the hub 127, is placed on the same side of the center of the sheave 88 as is the lug 89, and in radial alinement therewith, so that when said lug 89 is being 100 released from one of the stops, the upper end of the setting arm will be thrown toward the side of the mechanism opposite to said stop. The slots in the setting bars are so proportioned that when the setting arm 121 has its 105 upper end thus forced over, the pin 133 or 134 on the cam lever 106 or 107, as the case may be, will be engaged by the inner end of said slot so that the upper end of the cam lever will be forced outward, removing the 110 finger from the recess in the cam, leaving the cam free to rotate, and the lower end of said cam lever will be forced inward, where said lower end will be adapted to engage and limit the movement of its respective stop 115 thus limiting the crank shaft 55 to one-half revolution at each release. 120

It will be seen that by adjusting the crank disk 70 by means of the ratchet, the wrist pin 73 may be brought to such a position 125 relative to the lug 89 on the sheave 88 that during one half revolution the crank 74 will be rotated to close the valve 42, while during the other half revolution it will be rotated in the opposite direction to open the valve 42. 130

Since the lug 89, being released by the action of the cam, cam levers and stop on one side, is stopped by the stop on the opposite side, due to the relative positions of said stop and 5 its corresponding cam lever, which is held in position by the cam on such opposite side, it will be seen that the opening and closing of the valve 42 may be controlled according to the position of the cams. As these cams 10 revolve once in each twenty four hours, due to their operative connection with the clock mechanism, they will, if undisturbed, regularly control the positions of the cam levers and stops and, consequently, the rotation of 15 the crank shaft 55 and the opening and closing of the valve 42 which is in operative connection therewith.

The thumb knobs 52 and 53 are provided with the pointers 135 and 136 rigidly attached thereto, and the dial plate 51 is provided with the dials 137 and 138 concentric with the cam shafts 31 and 32, respectively. These dials 137 and 138 are divided and subdivided to indicate the hours and fractions 20 of hours in the day. The pointer on each thumb knob and the recess in the corresponding cam are given certain definite positions relative to each other so that the cam lever controlled by said cam will be allowed 25 to enter said recess and release the sheave and its operatively connected valve operating mechanism, instantaneously, when said pointer has reached a definite point on the dial. As the thumb knob, and consequently 30 the pointer, may be rotated with the cam independently of the cam gear, and clock mechanism with which it is in mesh, the pointer and the cam may be thus manually set at any desired position around the dial. 35 However, as soon as the cam is set to such position, the frictional engagement of the flat spring with the face of the cam gear will cause said cam to be rotated uniformly by the clock mechanism. Therefore, the time 40 at which this cam will reach the point at which it releases the cam lever may be determined by setting the pointer the proper proportionate distance around the dial from the above mentioned definite point. 45 As illustrated, I prefer to subdivide each of the divisions indicating the twenty four hours of the day into four parts and to number the graduations indicating the hours from "1" to "24" and from right to left 50 around the dials. The pointers should be turned in the opposite direction as indicated by the arrows on the dials, and each of the dials is labeled to indicate the operation which will take place upon the release of the 55 parts controlled by their respective cams. An ordinary clock dial is also provided upon the dial plate 51 concentric with the shaft 13, thus making it convenient for reference when 60 setting the cams.

65 As illustrated in Fig. 4, my improved au-

tomatic time valve is in the act of opening, the cam lever 107 having entered the recess 116, thus releasing the stop 91 and allowing the sheave 88 to turn past it and the pointer 136 having reached the graduation "24" on 70 the dial 138. The clock hands indicate the time as seven o'clock. Then supposing that it is desired that the valve should close at six o'clock, or eleven hours thereafter, the pointer 135 on the opposite dial is turned in 75 the direction of the arrow to the graduation "11" thereon. The cam lever 186 will be held in such position that the stop 98 will stop the sheave 88 when it has completed its one half revolution, and if the connecting rod 80 76 has been properly adjusted by means of the wrist pins 73 and 75 on the crank disk 70 and crank 74, respectively, the valve will have been opened during this one half revolution. Fig. 5 represents my invention when 85 the 11 hours have almost elapsed, the cam 37 having been rotated by the clock mechanism to a point where it is almost ready to release the cam lever 106 which controls the stop 90, and against which stop the lug 89 of the 90 sheave 88 is now bearing. It will be noted that the opposite cam lever 107 is now forced outward away from its supporting cam by the setting bar 129, so that it thus controls the stop 91 ready to stop the sheave 88 when 95 it has been released and has made its next one half revolution, closing the valve. While the setting mechanism is setting the cam lever which has last been released, it also increases the tension, and consequently the 100 effectiveness, of the contractile spring which draws the opposite cam lever against its respective cam, during the time when it is desirable that said spring should be most effective in order to cause the cam lever to 105 release the stop quickly.

From the above description it will be seen that once the times of opening and closing of the valves every day have been decided, it is only necessary to set the pointers around the 110 dials as above described, and to keep the clock main spring and valve operating main spring wound, after which my improved automatic time valve will continue to open and close regularly at the appointed times 115 every day without further attention. My invention thus is adaptable for use where it is desired to open and close any valve at regularly appointed times, it being especially adaptable for use with gas lamps for street 120 lighting in which case the lamps would be supplied with pilot burners, the construction and arrangement herein shown and described being provided with this end in view. As shown, the case 81, inclosing the mechanism, 125 is provided with gaskets 139 in its joints with its rear plate 80 and its door 140. To allow of convenience in adjusting the wrist pin 73, an opening 141 is provided in the rear plate 80, and a plate 142 is removably secured over 130

said opening and provided with a gasket 143. These gaskets are provided to make the case 81 dust and moisture proof. A starting mechanism is preferably provided for the 5 balance wheel of the clock mechanism, which consists of a wing 144 pivotally mounted in the arm 145 and rotatable, by means of the thumb knob 146, to engage said balance wheel, this starting mechanism being desirable 10 when the clock mechanism is permanently secured, rendering it inconvenient, should the clock stop, to start it by the ordinary method of shaking it slightly.

While the construction herein shown and 15 described is adaptable for daily automatic operation and more particularly for use with gas lights, I do not wish to be understood as limiting myself to it, but

What I claim as new and desire to secure 20 by Letters Patent is:

1. In an automatic time valve, the combination of a clock mechanism, a valve, a crank shaft journaled adjacent to said clock mechanism and to said valve, operative connection 25 between said valve and said crank shaft whereby said valve may be opened and closed by the rotation of said crank shaft, means for rotating said crank shaft, a sheave on said crank-shaft, a lug on said sheave, a 30 stop pivotally mounted adjacent to said sheave and operative connection between said stop and said clock mechanism whereby the operation of said cam is controlled, substantially as and for the purposes herein specified.

2. In an automatic time valve, the combination of a clock mechanism, a valve, a crank shaft journaled adjacent to said clock mechanism and said valve, operative connection 40 between said valve and said crank shaft whereby said valve may be opened and closed by the rotation of said crank shaft, a sheave on said crank shaft, a lug on said sheave, a stop pivotally mounted adjacent to said sheave and adapted to be engaged by 45 said lug, a cam lever adapted to engage said stop, a cam adapted to control said cam lever, and operative connection between said cam and said clock mechanism whereby the operation of 50 said cam is regulated, substantially as and for the purposes specified.

3. In an automatic time valve, the combination of a clock mechanism, a frame in which said clock mechanism is mounted, 55 means for supporting said frame, a crank shaft, bearings for said crank shaft on said frame, a crank disk adjustably mounted on said crank shaft, a valve adjacent to which said clock mechanism is supported, adjustable 60 operative connection between said valve and said crank disk, means for rotating said crank shaft, a sheave on said crankshaft, a lug on said sheave, a stop pivotally mounted adjacent to said sheave, and operative connection 65 between said stop and said clock

mechanism, whereby the operation of said stop is controlled, substantially as and for the purposes herein specified.

4. In an automatic time valve, the combination of a clock mechanism, a valve, a crank shaft journaled adjacent to said clock mechanism and to said valve, operative connection between said valve and said crank shaft whereby said valve may be opened and closed by the rotation of said crank shaft, 70 means for rotating said crank shaft, a sheave on said crank shaft, a lug on said sheave, a stop pivotally adjacent to said sheave and adapted to be engaged by said lug, a cam lever pivotally adjacent to said stop and adapted to engage said stop whereby said stop may be caused to limit the rotation of 75 said crank shaft, a finger on said cam lever, a cam rotatably mounted adjacent to said finger and having a recess adapted to receive 80 said finger whereby said cam lever may be allowed to disengage said stop to allow the rotation of said crank shaft and operative connection between said cam and said clock mechanism whereby the rotation of said cam 85 may be regulated, substantially as and for the purposes specified.

5. In an automatic time valve, the combination of a clock mechanism, a valve, a crank shaft journaled adjacent to said clock mechanism and to said valve, operative connection between said valve and said crank shaft whereby said valve may be opened and closed by the rotation of said crank shaft, 90 means for rotating said crank shaft, engaging means adapted to limit the rotation of said crank shaft, a cam adapted to control the operation of said engaging means, operative connection between said cam and said clock mechanism whereby the operation of 95 said cam is regulated, and a setting mechanism adapted to be controlled by the rotation of said crank shaft whereby the position of said engaging means relative to said cam and to said crank shaft may be controlled, 100 substantially as and for the purposes specified.

6. In an automatic time valve, the combination of a clock mechanism, a valve, a crank shaft journaled adjacent to said clock mechanism and to said valve, operative connection between said valve and said crank shaft whereby said valve may be opened and closed by the rotation of said crank shaft, 115 means for rotating said crank shaft, a sheave on said crank shaft, a lug on said sheave, a stop pivotally mounted adjacent to said lug adapted to be engaged thereby and yieldable thereto, a cam lever pivotally mounted adjacent to 120 said stop and adapted to engage said stop whereby it is caused to limit the rotation of said sheave and said crank shaft, a finger on said cam lever, a cam rotatably mounted adjacent to said finger and having a recess adapted to receive 125 said finger whereby said cam 130

lever may be allowed to release said stop and to allow the rotation of said sheave and said crank shaft, operative connection between said cam and said clock mechanism whereby 5 the rotation of said cam may be regulated, a setting arm pivotally mounted adjacent to said sheave, an engaging pin eccentrically mounted in said sheave and adapted to engage said setting arm to reciprocate it, and 10 engaging means between said setting arm and said cam lever whereby said finger may be alternatively removed from said recess or allowed to approach said cam to automatically produce the operation of said stop, substantially 15 as and for the purposes set forth.

7. In an automatic time valve, the combination of a clock mechanism, a valve, a cam shaft journaled adjacent said clock mechanism and said valve, operative connection between said valve and said crank shaft whereby said valve may be opened and closed by the rotation of said crank shaft, means for rotating said crank shaft, a sheave on said crankshaft, a lug on said sheave, a 20 stop pivotally mounted adjacent to said sheave, a cam adapted to control the operation of said stop, and adjustable operative connection between said cam and said clock mechanism whereby the operation of said 25 cam may be regulated by said clock mechanism and whereby the position of said cam is allowed to be regulated independently of said clock mechanism, substantially as and for the purposes specified.

8. In an automatic time valve, the combination of a clock mechanism, a valve, a crank shaft journaled adjacent to said clock mechanism and to said valve, operative connection between said valve and said crank 30 shaft whereby said valve may be opened and closed by the rotation of said crank shaft, means for rotating said crank shaft, a lug on said sheave, a stop pivotally mounted adjacent to said sheave, a cam adapted to control 35 the operation of said stop, adjustable operative connection between said cam and said clock mechanism whereby the operation of said cam is regulated and whereby said cam is allowed to be rotated independently of 40 said clock mechanism, a pointer adapted to rotate with said cam and a dial adapted to be traversed by said pointer and whereby the position of said cam relative to said engaging means may be indicated, substantially as and 45 for the purposes specified.

9. In an automatic time valve, the combination of a clock mechanism, a valve, a crank shaft journaled adjacent to said clock mechanism and to said valve, operative connection 50 between said valve and said crank shaft whereby said valve may be opened and closed by the rotation of said crank shaft, means for rotating said crank shaft, a sheave on said crank shaft, a lug on said sheave, a stop pivotally mounted adjacent to said sheave and 55

adapted to be engaged by said lug, a cam lever pivoted adjacent to said stop and adapted to engage said stop whereby said stop may be caused to limit the rotation of said crank shaft, a finger on said cam lever, a cam 60 rotatably mounted adjacent to said finger and having a recess adapted to receive said finger whereby said cam lever may be allowed to disengage said stop to allow the rotation of said crank shaft, adjustable operative connection between said crank and said clock mechanism whereby the rotation of said cam may be regulated by said clock mechanism and whereby it is allowed to be rotated independently of said clock mechanism, a pointer adapted to rotate with said cam independently of said clock mechanism, a dial adapted to be traversed by said pointer and divisions on said dial whereby the position of said recess relative to said finger may 65 be indicated by said pointer, substantially as and for the purposes set forth.

10. In an automatic time valve, the combination of a clock mechanism, a valve, a crank shaft journaled adjacent to said clock mechanism and to said valve, operative connection between said valve and said crank shaft whereby said valve may be opened and closed by the rotation of said crank shaft, means for rotating said crank shaft, a sheave 70 on said crank shaft, a lug on said sheave, a stop pivotally mounted adjacent said sheave and adapted to be engaged by said lug, a cam lever pivotally mounted adjacent to said stop and adapted to engage said stop whereby said stop may be caused to limit the rotation of said crank shaft, a finger on said cam lever, a cam 75 rotatably mounted adjacent to said finger and having a recess adapted to receive said finger whereby said cam lever may be allowed to disengage said stop to allow the rotation of said crank shaft, operative connection between said cam and said clock mechanism whereby the rotation of said cam may be regulated, an engaging pin eccentrically 80 mounted on said sheave, a setting arm pivotally mounted adjacent to said sheave and adapted to be reciprocated by said engaging pin, a setting arm pivotally mounted adjacent to said sheave and adapted to be reciprocated by said engaging pin, a setting bar pivotally attached to said setting arm and slidably attached to said cam lever whereby said cam lever may be allowed to enter said recess in said cam or be removed therefrom, substantially as and for the purposes specified.

11. In an automatic time valve, the combination of a clock mechanism, a valve, a crank shaft journaled adjacent said clock mechanism and to said valve, operative connection between said valve and said crank shaft, means for rotating said crank shaft, a sheave on said crank shaft, a lug on said sheave, a stop pivotally mounted adjacent to said sheave 120

and adapted to be engaged by said lug, a spring attached to said stop and adapted to oppose said stop to said lug, a fence adapted to be engaged by said lug and to oppose the tension of said spring, and controlling means for said lug whereby said stop may be caused to alternatively limit the rotation of said sheave and said crank shaft or to allow the rotation thereof, substantially as and for the 10 purposes specified.

12. In an automatic time valve, the combination of a clock mechanism, a valve, a crank shaft journaled adjacent to said clock mechanism and to said valve, operative connection between said valve and said crank shaft whereby said valve may be opened and closed by the rotation of said crank shaft, means for rotating said crank shaft, a stop adapted to limit the rotation of said crank 15 shaft, a cam lever pivoted adjacent to said stop whereby the operation of said stop is controlled, a cam mounted adjacent to and adapted to control the operation of said cam lever, operative connection between said cam 20

25 and said clock mechanism whereby the operation of said cam is regulated, a setting arm adapted to be reciprocated by means of said crank shaft, a setting bar pivotally attached to said setting arm and slidably attached to 30 said cam lever whereby said cam lever may be alternatively forced away from said cam or allowed to approach it and a spring secured to said setting arm and to said cam lever whereby said cam lever may be drawn 35 toward said cam and whereby the tension of said spring is increased or diminished, substantially as and for the purposes specified.

13. In an automatic time valve, the combination of a clock mechanism, a frame in 40 which said clock mechanism is mounted, a crank shaft, bearings for said crank shaft on said frame, a valve adjacent said frame, adjustable operative connection between said valve and said crank shaft whereby said 45 valve may be opened and closed by the rotation of said crank shaft, means for rotating said crank shaft, engaging means adapted to limit the rotation of said crank shaft, a cam spindle mounted on said frame, a hollow cam 50 shaft journaled on said cam spindle, a cam gear mounted on said cam shaft and rotatable relative thereto, a pinion in mesh with said cam gear and operatively connecting it to said clock mechanism whereby the rotation 55 of said cam gear is regulated, a spring mounted on said cam shaft to rotate therewith and bearing against said cam gear whereby an adjustable connection is formed between said cam shaft and said cam gear, a 60 cam mounted on said cam shaft and adapted to rotate therewith, and a cam lever adapted to be controlled by said cam and to control said engaging means whereby the rotation of said crank shaft is limited, substantially as 65 and for the purposes specified.

14. In an automatic time valve, the combination of a clock mechanism, a valve, a crank shaft journaled adjacent to said clock mechanism and to said valve, operative connection between said valve and said crank 70 shaft whereby said valve may be opened by one part of the rotation of said crank shaft and whereby it may be closed by another part of the rotation of said crank shaft, a sheave on said crank shaft, a lug on said 75 sheave, a stop pivoted adjacent to said sheave and adapted to be engaged by said lug to limit the opening of said valve, a stop pivoted adjacent to said sheave and adapted to be engaged by said lug to limit the closing 80 of said valve, cam levers pivoted adjacent to said stops and adapted to control their respective operations, cams mounted adjacent to and adapted to control the operation of said cam levers, and operative connection between said cams and said clock mechanism, whereby the operation of said cams is regulated, substantially as and for the purposes 85 specified.

15. In an automatic time valve, the combination of a clock mechanism, a valve, a crank shaft journaled adjacent to said clock mechanism and to said valve, operative connection between said valve and said crank shaft whereby said valve may be opened by 90 one part of the rotation of said crank shaft and whereby said valve may be closed by another part of the rotation of said crank shaft, means for rotating said crank shaft, a sheave on said crank shaft, a lug on said 95 sheave, a stop pivoted adjacent to said sheave and adapted to be engaged by said lug to limit the opening of said valve, a stop pivoted adjacent to said sheave and adapted to be engaged by said lug to limit the closing 100 of said valve, cam levers pivoted adjacent to said stops and adapted to control their respective operations, cams mounted adjacent to and adapted to control the operations of said cam levers, adjustable operative connections between said cams and said clock mechanism whereby the operations of said cams are regulated by said clock mechanism and whereby the positions of said cams relative to said cam levers may be 105 regulated independently of said clock mechanism to predetermine the times of opening and closing of said valves, substantially as 110 set forth.

16. In an automatic time valve, the combination of a clock mechanism, a frame in which said clock mechanism is mounted, a crank shaft, bearings for said crank shaft on said frame, a valve adjacent to said frame, adjustable operative connection between 120 said crank shaft and said valve whereby said valve may be opened by one part of the rotation of said crank shaft and whereby said valve may be closed by another part of the rotation of said crank shaft, means for 125 the rotation of said crank shaft, means for 130

- rotating said crank shaft, a sheave on said crank shaft, a lug on said sheave, a stop pivotally mounted adjacent to said sheave and adapted to be engaged by said lug to limit 5 the opening of said valve, a stop pivotally mounted adjacent to said sheave and adapted to be engaged by said lug to limit the closing of said valve, springs attached to and adapted to oppose said stops to said lug and 10 to allow them to yield thereto, fences adapted to be engaged by said stops to oppose the tension of said springs, cam levers pivoted adjacent to and adapted to engage said stops whereby they are caused to limit the 15 opening and closing of said valve, fingers on said cam levers, cam spindles mounted on said frame adjacent to said fingers on said cam levers, hollow cam shafts journaled on said spindles, cam gears mounted on said 20 cam shafts and rotatable relative thereto, a pinion in mesh with said cam gears and forming an operative connection with said clock mechanism, springs mounted on said cam shafts, adapted to rotate therewith and en- 25 gaging said cam gears whereby adjustable connections are formed between said cam gears and said cam shafts and whereby said cams may be rotated independently of said cam gears, cams mounted on said cam shafts 30 adapted to rotate therewith and having re- cesses adapted to receive said fingers on said cam levers, a setting arm pivotally attached to said frame adjacent to said sheave, an engaging pin eccentrically mounted in said sheave and in engagement with said setting 35 arm whereby said setting arm may be reciprocated, setting bars pivotally attached to said setting arm and slidably attached to said cam levers whereby said fingers on said cam levers may be alternatively removed 40 from said recesses in said cams or be allowed to enter said recesses, springs attached to said setting arm and to said cam levers whereby said cam levers may be caused to approach said cams and whereby the ten- 45 sion of said springs may be alternatively increased or diminished to cause the said cam levers to approach said cams or to allow them to recede from said cams, pointers adapted to rotate with said cam shafts, and dials adapt- 50 ed to be traversed by said pointers whereby the positions of said cams relative to said cam levers may be indicated to predetermine the times of opening and closing of said valve, substantially as set forth.

ARCH A. SHINGLETON.
